UNITED STATES PATENT OFFICE.

BENJAMIN DICKSTEIN, OF BROOKLYN, NEW YORK.

DESIGN FOR A SHOE.

Application filed May 7, 1924. Serial No. 9,515. Term of patent 3½ years.

To all whom it may concern:

Be it known that I, BENJAMIN DICKSTEIN, a citizen of the United States, residing at the city of New York, borough of Brooklyn, Kings County, in the State of New York, have invented a new, original, and ornamental Design for Shoe, of which the following is a specification, reference being had to the accompanying drawing, forming part thereof.

In said drawing—

Figure 1 is a perspective view showing a shoe constructed according to and embodying my said invention, and

Fig. 2 is a side elevation of the same.

I claim:

The ornamental design for a shoe, as shown.

BENJAMIN DICKSTEIN.
